UNITED STATES PATENT OFFICE.

RICHARD S. GIESE, OF PITTSBURGH, PENNSYLVANIA.

DESIGN FOR A SINGLE-UNIT REFLECTOR.

51,690.

Specification for Design. Patented Jan. 15, 1918.

Application filed October 9, 1917. Serial No. 195,646. Term of patent 7 years.

To all whom it may concern:

Be it known that I, RICHARD S. GIESE, a citizen of the United States, residing at Pittsburgh, in the county of Allegheny and State of Pennsylvania, have invented a new, original, and ornamental Design for Single-Unit Reflectors, of which the following is a specification.

Referring to the drawing—

Figure 1 is a side elevation, showing my new design;

Fig. 2 is a top plan view of the same; and

Fig. 3 is a bottom plan view.

I claim,

The new, original and ornamental design for a single unit reflector, substantially as shown.

In testimony that I claim the foregoing as my own, I have hereto affixed my signature in the presence of two witnesses.

RICHARD S. GIESE.
